HYDRAULIC PUMP OR MOTOR

Maurice Kerr Ingolby, London, England, assignor to The Variable Speed Gear Limited, London, England, a company of Great Britain

Application April 6, 1938, Serial No. 200,441
In Great Britain October 1, 1937

1 Claim. (Cl. 103—38)

This invention relates to hydraulic pumps, motors and other apparatus embodying mechanism of the swashplate type and more particularly to means for controlling the tilting of the swashplate in apparatus of that type.

Hitherto it has been the practice in connection with pumps of the swashplate type to control the tilting member or swashplate by means of a series of levers and rods coupled to a pressure operated ram acting against a spring, the ram, the cylinder in which the ram is disposed and spring being arranged externally of the pump casing.

It is the chief object of the invention to provide an improved controlling arrangement for the tiltable member or swashplate which although being particularly adapted for small units may also be adapted for any type of pump, motor or other apparatus employing mechanism of the swashplate type.

According to the invention the angulation of the tiltable member or swashplate is controlled automatically by means disposed within the casing of the apparatus. Preferably controlling members are associated with the rotating parts including the swashplate and are adapted to rotate therewith while one or more non-rotating pressure operated elements are disposed within a stationary member, said pressure operated elements being adapted to act on the rotating parts against the action of the control members to vary the inclination of the tiltable member or swashplate according to the pressure conditions prevailing within the pressure system. Preferably, two or more springs or the like are provided each of which is associated at one end with the rotatable swashplate or part associated therewith and at the other with a member which is also adapted to rotate while a plurality of control rams or the like are disposed within a stationary member, said rams being adapted on operation to act in opposition to the springs to vary the angle of inclination of said swashplate. The control rams, of which there may be any desired number, for example three, are preferably disposed within the normal cylinder block and are adapted to be actuated according to the liquid pressure obtaining in the delivery side of the cylinder block, i. e. in the pressure system, the motion of the rams being preferably transmitted through a thrust collar and ball race to a rotatable member which in turn is adapted to act on the swashplate.

In order that the said invention may be clearly understood and readily carried into effect the same will now be more fully described with refer-

ence to the accompanying drawings, which show one embodiment by way of example and in which:

Figure 1 shows partly in section the relevant parts of a pump embodying the invention.

Figure 2 is a cross sectional view.

Referring to the drawings, 10 denotes a tiltable member or swashplate which is mounted in known manner on a driven shaft 11 and is adapted to be tilted from a vertical or no-stroke position indicated in dotted lines into for example the full stroke position shown in full lines or any other intermediate position to effect actuation of a plurality of pistons such as that indicated at 12. The outer ends of the connecting rods such as 13, are supported in known manner in a non-rotatable socket ring 14 carried by the swashplate 10, while the pistons themselves are adapted to slide in cylinders such as 15 which are formed in a stationary cylinder block or barrel 16 and provided with inlet and outlet ports 15' communicating with a valve chamber not shown. In accordance with the invention two springs 17 are associated with the swashplate 10 and are adapted to rotate therewith, said springs being disposed one on either side of the shaft 11. The springs 17 are associated with guide members 18 which latter are in the embodiment illustrated secured to the rear face of the rotating swashplate 10 by means of pins 19 which are anchored in suitable elements 20 formed integrally with or mounted on said swashplate. The mating members 21 at the opposite ends of the springs 17 are anchored to a rotating thrust plate 22 by means of similar pins 23 and elements 24. The plate 22 is, as can be seen from the drawings, mounted on the shaft 11 and is adapted to rotate therewith and the arrangement is preferably such that suitable rollers or other thrust bearing members are interposed in known manner between the rear face of the plate 22 and a stationary part of the casing of the pump. 40 Mounted in suitably disposed cylinders 25 within the cylinder block 16 are a plurality of rams or the like 26 and in the present embodiment three such rams are provided which are spaced evenly around the block 16. The cylinders 25 in which the rams 26 are disposed are adapted to communicate through the medium of suitable channels or conduits such as are indicated at 27 in the cylinder block 16 with the delivery side of the pump which is in communication with the pressure system so that the rams 26 will be subjected to the pressure of the liquid on the delivery side of the cylinder block, i. e. the pressure in the pressure system as distinct from the normal pressure existing in the apparatus casing. The rams 26 are adapted when 55

in their operative position to bear against a thrust ring or the like 28 which carries the outer race 29 of a ball bearing, the inner race 30 of which is mounted on a member 31 which is in turn adapted 5 to slide axially on the driven shaft 11 but is rotatable therewith. The slide member 31 is as can be seen from the drawings formed with a sleeve-like portion 32 adapted to surround the shaft 11 and to serve as a seat for the inner race 30 of 10 the ball bearing. A flange 33 is formed integrally with the sleeve portion 32 and is adapted to project radially thereof and of the shaft 11. Means are also associated with the swash mechanism adapted positively to prevent any rotation thereof 15 and thereby to ensure that no side load will be transmitted to the pistons. As can be seen from Figure 2 such means preferably comprise a yoke or the like 36 which is mounted for universal movement about a fixed point such as for example 20 the apparatus casing by means of a suitable ball connection 37 and is adapted to embrace the socket ring 14, its outer ends being freely journaled on projections 38 formed integrally with said ring. The yoke 36 while preventing rotation 25 of the swash mechanism does not hinder the tilting thereof.

In operation, when the shaft 11 is rotating and the swashplate 10 is in the full-stroke position shown in the drawing, liquid will be delivered by 30 the pistons 12, which are reciprocated by the swashplate, through the ports 15' to the delivery side of the pump and also to the channels or conduits 27 in the cylinder block 16 which communicate with the cylinders 26 housing the rams 35 26. The external resistance to the flow of liquid from the pump will cause the pressure within the cylinders and the entire pressure system to rise and on reaching a predetermined value the pressure acting on the rams 26 will cause the latter 40 to move forwardly. The movement of the rams results in a forward movement of the thrust ring 28, the ball bearings and the sliding member 31, which by virtue of the roller contact between the flange 33 and the swashplate 10 causes the latter 45 to tilt against the action of the control springs 17 towards the vertical or no-stroke position indicated in dotted lines. Should the pressure on the delivery side of the pump be decreased the springs 17 will overcome the action of the rams 26 and 50 will again urge the swashplate 10 towards the full stroke position. By virtue of the invention therefore the pump delivery is controlled between maximum and zero within any predetermined

limits of pressure. Further it will be appreciated that since rotation of the swash mechanism is positively prevented by virtue of the provision of the yoke 36 no side load will be transmitted to the pistons. 5

The arrangement above described and illustrated is particularly adapted for use in apparatus which also incorporates any or all of the inventions forming the subject of our co-pending patent applications Nos. 200,437 and 200,440, filed 10 April 6, 1938.

Further while the controlling arrangement according to the invention is also particularly adapted for use in small pumps of the swashplate type its application is not limited thereto since 15 it may be applied to any pump of the swashplate type and also in certain cases to motors and other units employing swashplate mechanism.

What I claim and desire to secure by Letters Patent of the United States is: 20

A hydraulic unit operating with a hydraulic pressure system and having a casing, swashplate mechanism including a shaft, a swashplate, a non-rotating cylinder block having a plurality of cylinders therein, and pistons operatively connected to said swashplate and reciprocating in said cylinders, the whole being disposed within said casing, the combination of a plurality of resilient members disposed within said casing on that side of the swashplate remote from the cylinder block while being associated with said swashplate to rotate therewith, a plurality of auxiliary cylinders in said cylinder block open to the pressure prevailing in the hydraulic system of said hydraulic unit, a plurality of rams in addition to said pistons adapted to reciprocate in said auxiliary cylinders, a member rotatable with the shaft and slideable relatively thereto, said member being interposed between the rams and the swashplate, bearing means therefor including an inner 25 ball race mounted on said member rotating with the shaft, ball bearings, and an outer race with which said rams are adapted to cooperate, and a roller member associated with said swashplate with which said rotatable and slideable member is 30 adapted to cooperate on movement thereof under the action of the rams so that a force will be transmitted to the swashplate against the action of the resilient members so as to vary the inclination of the swashplate in accordance with the 35 pressure conditions prevailing within said hydraulic pressure system of said hydraulic unit. 40 45 50

MAURICE KERR INGOLDEBY.
